UNITED STATES PATENT OFFICE

2,553,435

DECK SCALER

Lester E. Briese, Galveston, Tex., assignor to
 Todd Shipyards Corporation, New York, N. Y.,
 a corporation of New York

Application December 21, 1948, Serial No. 66,487

1 Claim. (Cl. 29—81)

1

This invention relates to a deck scaler, and more particularly to a machine for removing scale, paint, and other deposits from the deck of a ship. While primarily intended for scaling a ship deck, it is to be understood that the invention is equally useful in any situation requiring the scaling or chipping of a surface of large area.

A general object of this invention is to provide a simple machine actuated by compressed fluid for performing a scaling operation.

Another object is to provide a deck scaler having a plurality of scaler heads having scaling tools whose operation is controlled by a single conveniently accessible means.

A further object of the invention is to provide a novel arrangement of scaling tools, whereby a broad surface may be scaled in a single pass of the machine.

Another object is to provide novel means for mounting the scaler heads on the frame of the machine, whereby shock and vibration, due to the reciprocation of the scaling tools, will be reduced to a minimum.

A further object is to provide novel handle means for both propelling the deck scaler machine over the surface of the deck, and also controlling the supply of fluid to the scaler heads.

Further objects and advantages of the invention will appear in the following description and in the appended drawings, wherein is illustrated a preferred embodiment of the invention. The broad scope of the invention is pointed out in the appended claim.

In the accompanying drawings, wherein like numerals refer to like parts throughout:

Figure 1 is a top plan view of the deck scaler in accordance with this invention.

Figure 2 is a partial sectional view taken on the line 2—2 of Figure 1.

Figure 3 is a front elevation as viewed from the right hand side of Figure 1.

Figure 4 is a bottom plan view, and

Figure 5 is a partial sectional view taken on the line 5—5 in Figure 4.

Referring to the drawings, 11 indicates the frame of the deck scaler and is shown in the form of a flat horizontal plate. Along each of two opposite edges the frame 11 has downwardly depending flanges 12 and 13, as best seen in Figures 3 and 4. At one forward corner of the frame 11 and rigidly secured to the flange 12 is a wheel support 14. At the other forward corner of the frame 11 and rigidly secured to the flange 13 is a wheel support 15. Centrally of the rear edge of the frame 11 is a wheel support 16. The supports 14, 15 and 16 each have a pair of downwardly depending lugs or flanges 17, and a roller

2

or wheel 18 is rotatably mounted therein by means of a headed pin 23 locked in position by a cotter key 24.

Rigidly secured to the lower surface of the frame 11 and adjacent the rear edge thereof is a long tubular manifold 19. As shown in Figure 4, the manifold has closure caps 21 at each end and is pivotally secured to the frame 11 within trunnions 20.

10 Within the lower surface of frame 11 a plurality of somewhat elliptical recesses 34 are formed, and mounted within the recesses 34 are cup-like shock absorbers 35 composed of rubber or other similarly resilient material. Mounted within the 15 shock absorbers 35 are the scaler heads 32, as best shown in Figure 5.

The scaler heads 32 may be of any conventional type, and since their internal construction is well known to those skilled in the art, the details of 20 such construction will not be described herein, except to state briefly that the scaler heads 32 have a plurality of scaling tools 33 depending therefrom as best shown in Figure 3. The particular scaler heads 32 shown in this illustration

25 of the invention are known as the "Oldham" type, and each has three scaling tools 33 arranged in a straight horizontal row. The scaling tools 33 are caused to reciprocate vertically so as to chip or scale paint and other deposits from the 30 surface, as is well known in the art. It is to be understood that the specific type and construction of scaler heads 32 and scaling tools 33 form no part of this invention and any equivalent type of scaler head may be substituted for the "Oldham" type disclosed herein.

In order to secure the scaler heads 32 and cup-like shock absorbers 35 within the recesses 34, a plurality of U-shaped tie bolts 36 may be employed. Each of the tie bolts 36 comprises a

40 pair of vertical legs 37 connected by a lower base portion 38, as best shown in Figure 2. The vertical legs extend upwardly through the frame 11 and are secured to the frame 11 by means of washers 48 and nuts 39. The lower or bight

45 portions 38 of the U-shaped tie bolts 36 engage the lower surfaces of the scaler heads 32 so as to draw said heads 32 and the shock absorbers 35 up into the recesses 34 and securely hold them in place therein. Two tie bolts 36 are preferably employed for each scaling head, one of the tie bolts extending between two adjacent scaling tools 33.

The relative arrangement and location of the 50 scaler heads 32 will be noted. A row or series of scaler heads 32 is disposed perpendicular to the forward direction of movement of the deck scaler (which is to the right as viewed in Figure 1). The scaler heads 32 of said forward row are

3

suitably spaced and a second row of scaler heads 32, parallel to the first row and perpendicular to the direction of forward movement of the deck scaler, is located rearwardly of said first row. Each of the scaler heads 32 of the second row is located opposite the space between two scaler heads of the first row. It will be thus seen that this overlapping relation enables a broad surface to be scaled in a single pass of the machine. The several scaling tools 33 of each scaler head 32 are equi-distantly spaced from one another. Furthermore, the scaling tools at the extreme ends of each scaler head of one row are spaced, in a direction transverse to the direction of movement of the deck scaler, from the adjacent scaling tool in the other row a distance equal to the distance between the several scaling tools of each head. In other words, it will be seen in Figure 4 that the transverse offset distance between scaling tool 33' and scaling tool 33'' will be the same as the distance between scaling tool 33' and scaling tool 33'''. By this arrangement movement of the deck scaler will result in the several scaling tools moving along parallel paths. The above-noted overlapping arrangement of the scaler heads 32 permits the several scaling tools 33 of the different scaler heads 32 to be equi-distantly spaced laterally of the machine and its movement.

Each scaling tool 33 will remove paint over an area of sufficient lateral extent that during a single pass of the machine over a deck, it will remove all paint and scale within the area bounded by the two laterally outermost tools.

Extending rearwardly and horizontally from each of the scaler heads 32 is a metallic tube or duct 40. In alignment with these tubes 40, are manifold discharge tubes 31, as shown in Figure 4. Leading from each of the manifold discharge tubes 31 to each of the tubes 40 is a flexible hose 41.

Referring to Figure 2, a pipe 22 is secured to the manifold 19 and extends upwardly and rearwardly of the manifold 19 and has a valve connection 25 at its upper end. The valve 25 is actuated by the handle 26. Extending from the valve 25 is a pipe 52 having at the upper end thereof a hollow cross-bar handle 27. As shown in Figure 1, the handle 27 has a closure cap 28 at one end and a hose 29 secured to the other end by means of a conventional hose clamp 30.

Operation

It will be thus seen that the wheels 18 allow the frame 11 to be rolled along the surface of a deck by means of the operator pushing or pulling on the cross-bar handle 27. The hose 29 may be connected to any suitable source of supply of compressed fluid or gas (not shown). It is to be understood that the term "fluid" as used in this specification and the appended claim 60 includes air, steam, water or any other gaseous or liquid fluid. The compressed fluid enters the hollow cross-bar handle 27, flows down through the pipe 52 and, assuming that the valve 25 has been opened by means of handle 26, the compressed fluid will flow down through the pipe 22 and into the manifold 19. It is thus evenly distributed to the several scaler heads 32 through the tubes 31, 41 and 40. As is well known, the scaler heads 32 will apply the energy of the compressed fluid to cause the scaling tools 33 to vertically reciprocate, whereby the lower ends 42 of the scaling tools 33 will chip and scale paint or other deposits from the surface being worked on.

4

In addition to providing a simple effective means for supplying compressed fluid to the manifold 19, the arrangement comprising pipes 22 and 52, valve 25, hollow cross-bar handle 27, and hose 29, also provides a convenient means for propelling the machine along the deck, and also a valve means conveniently accessible to the handle for controlling the operation of the scaler heads 32.

The above-described specific embodiment of the invention is intended to be merely illustrative, the scope of the invention being indicated by the appended claim.

I claim:

15 A deck scaling machine of the class described comprising a frame having spaced depending bearings, rollers mounted in said bearings for supporting the frame above the surface of a deck over which the machine is moved, the underside of said frame having transversely spaced rows of recesses, inverted cup-shaped shock absorbers mounted in said recesses and having depending flanges, scaler heads having their upper end portions insertable in said shock absorbers and yieldably engaging said flanges, a manifold mounted on the underside of the frame at the rear end thereof, said manifold having spaced flexible tubings connecting the same with said scaler head, a tubular member extending upwardly and rearwardly from the center of said manifold and having a tubular cross bar handle at its upper end, said handle having a closed end and its opposite end connected with a tube for introducing compressed fluid into each of the 20 scaler heads, vertical reciprocating scaler tools mounted in each of said scaler heads and extending downwardly and outwardly therefrom so as to insure maximum impact and scaling efficiency during the operation of the machine, each scaler head having associated therewith spaced pairs of substantially U-shaped tie bolts, each of said tie bolts having a pair of downwardly depending arms connected by a transverse base portion, said arms engaging the flanges of said shock absorbers and extending upwardly through openings in the frame, means for detachably connecting the arms to the frame, and said base portions extending under and supporting an adjacent scaler head and between adjacent scaler tools so as to maintain the same in proper operative positions during the operation of the machine, said scaler tools being disposed substantially parallel to the transverse rows of scaler heads and uniformly spaced laterally from adjacent scaler tools in a direction perpendicular to the path of movement of the machine so as to completely scale an area of the deck equal to the width of the manifold in a single pass of the machine.

LESTER E. BRIESE.
